UNITED STATES PATENT OFFICE.

HOWARD J. KERR, OF BAYONNE, NEW JERSEY, ASSIGNOR TO THE BABCOCK & WILCOX COMPANY, OF BAYONNE, NEW JERSEY, A CORPORATION OF NEW JERSEY.

ECONOMIZER FOR TRANSVERSE-DRUM BOILERS.

1,345,369.

Specification of Letters Patent.

Patented July 6, 1920.

Application filed May 4, 1918. Serial No. 232,478.

To all whom it may concern:

Be it known that I, HOWARD J. KERR, a citizen of the United States, residing at Bayonne, in the county of Hudson and State 5 of New Jersey, have invented a new and useful Improvement in Economizers for Transverse-Drum Boilers, of which the following is a full, clear, and exact description.

10 My invention relates to boilers of the general Stirling type, wherein upper transverse water drums are connected by banks of tubes to a lower transverse mud drum or drums, the gases being given serial up and down 15 passes over the heating surface by suitable baffling. The object of the invention is to provide a simple and compact economizer system in connection with such boilers, to improve the efficiency of the economizer 20 system, and to provide for short circuiting of the gases over the economizer, if desired.

In the drawings Figure 1 is a sectional side elevation of a Stirling boiler with economizer constructed in accordance with 25 my invention; Fig. 2 is an enlarged detail view of the short-circuiting damper; and Figs. 3, 4 and 5 are front elevations partly broken away showing different arrangements of the superimposed economizer boxes 30 located in the rear of the front surface of the rear wall of the setting.

In the drawings 2, 3 and 4 represent transverse steam and water drums connected by banks of tubes 5, 6 and 7, respectively, 35 with a lower transverse mud drum 8.

I have shown the drums 3 and 4 as connected by water circulators 9, and the steam space of the front and rear drums is connected to the middle drum by steam circulators 10. The steam may be taken off either 40 the middle or rear upper drum. I have also shown the boiler as fired by underfeed stokers 11, located under the front wall 12 of the setting.

45 At the rear of the rear bank of water tubes, I show a feed water heater or economizer comprising rows of water tubes 13, connected at their upper ends to the water space of the rear steam and water drum 2, 50 while their lower ends are bent rearwardly and enter transverse boxes 14, shown as

located in a pocket in the rear wall formed by suitable transverse metallic members 15. By locating these cross boxes in the rear of the chamber of the setting, a more compact setting is obtained, and the lower parts of the economizer tubes are more effective where the gases flow downwardly over these tubes. I have shown the baffling as comprising a baffle 16, extending from the mud drum 60 upwardly along the rear of the front bank, and baffle 17, extending downwardly from the upper drum 3 between the last two rows of tubes, and a baffle 18 extending upwardly from a damper 19, coacting with the mud 65 drum, to a point short of the drum 2. The damper 19 is mounted on a transverse shaft extending through the setting and which may be set at different angles by an external stop or handle 20 (Fig. 2), held by 70 suitable pins or stop members 21. The damper may thus be held in closed position, as shown in full lines in Fig. 2, or in open position, as shown in dotted lines therein.

The gases, therefore, flow upwardly 75 through the front bank, pass over the inverted U-tube superheater 22, and down over the majority of the tubes of the middle bank, thence rise over the last tubes of the middle bank and the tubes of the rear bank, and 80 then descend over the tubes of the feed water heater or economizer to the outlet 23.

I thus obtain economical results in the feed water heater or economizer, as the entering water flows upwardly through the 85 tubes 13, while the gases flow downwardly thereover, in accordance with the counter-flow principle. If it is desired at any time to cut out the economizer, the damper 19 may be opened, whereupon the gases will 90 short circuit from the lower part of the baffle 17 directly to the outlet 23. This damper may or may not be used as desired, and if not used, the baffle 18 may be extended down to the mud drum 8. 95

In all forms, the feed water preferably enters the lowermost of the boxes 14. In Fig. 3, the feed water enters through valve connection 24 into a vertical box 25 at the end of the boxes 14, and thence through 100 nipples into the end of each box, flowing in parallel therethrough. The boxes are

provided with suitable handholes 26, opposite the tubes.

In the form of Fig. 4, the feed water enters one end of the lowermost box through valve connection 24^a, and thence flows serially through boxes which are connected at alternate ends by nipples 27.

In the form of Fig. 5, the water enters the center of the lowermost box through section 24^b, rises through nipples 28 into the next cross box, thence through nipples 29 into the third cross box, and thence through nipples 30 into the top cross box, these nipples to be staggered, as illustrated. In all forms, the cross boxes are provided with suitable handholes or closures for access to the tube ends.

The advantages of my invention will be obvious to those skilled in the art, since a very compact setting is made possible. The counterflow principle gives efficiency in the economizer tubes, and the damper, if used, provides for short circuiting of the gases.

In my arrangement, there is a substantially continuous upward flow of water through the economizer tubes, thus preventing the hot water in the upper drums flowing downward through the economizer tubes. The temperature conditions are substantially balanced between the economizer tubes, the temperature being lowest at the lowermost point of the economizer and gradually increasing along the tubes from the bottom to the top, thus leading to a maximum efficiency through the action of the counterflow principle. There is a balancing of circulation between the economizer tubes, these tubes at any level being of substantially the same temperature.

Changes may be made in the form and arrangement of the boiler, the number of drums, the arrangement of the banks of tubes, etc., without departing from my invention.

What I claim and desire to secure by Letters Patent of the United States is—

1. A boiler of the general Stirling type having transverse upper drums connected by banks of tubes to a lower transverse drum or drums, baffling arranged to give the gases serial up and down passes over the tubes, a rear economizer having tubes within the setting and their upper ends connected to one of the upper transverse drums, and their lower ends bent rearwardly, and a plurality of cross boxes located at the rear of the setting to which the lower ends of the economizer tubes are connected.

2. A boiler of the general Stirling type having transverse upper drums connected by banks of tubes to a lower transverse drum or drums, a set of rear economizer tubes the upper ends of which are connected to the water space of the rear steam and water drum, and a plurality of superimposed

water boxes at the rear of the setting, the lower ends of the economizer tubes being bent rearwardly and connected to said boxes.

3. A boiler of the general Stirling type having transverse upper drums connected by banks of tubes to a lower transverse drum or drums, a set of economizer tubes the upper ends of which are connected to the water space of the rear steam and water drum, a plurality of superimposed water boxes at the rear of the setting, the lower ends of the economizer tubes being bent rearwardly and connected to said boxes, a water inlet connection for said boxes whereby the water is caused to flow upwardly through the economizer tubes, and baffling arranged to give a down pass over the economizer tubes and across the bent lower ends thereof.

4. A boiler of the general Stirling type having transverse upper drums connected by banks of tubes to a lower transverse drum or drums, a baffle in the rear of the rear bank of tubes, economizer tubes back of said baffle, the upper ends of said economizer tubes being connected to the rear steam and water drum and the lower ends of said tubes being bent rearwardly, a plurality of water boxes at the rear of the setting to which the lower ends of the economizer tubes are connected, and a feed water inlet for the boxes arranged to cause an upward flow through the economizer tubes.

5. A boiler of the general Stirling type having transverse upper drums connected by banks of tubes to a lower transverse drum or drums, a baffle in the rear of the rear bank of tubes, economizer tubes back of said baffle, the upper ends of said tubes being connected to the rear steam and water drum and the lower ends of said tubes bent rearwardly, water boxes at the rear of the setting to which the lower ends of the economizer tubes are connected, a feed water inlet for the boxes arranged to cause an up-flow through the economizer tubes, and an adjustable damper at the lower end of the rear baffle.

6. A boiler of the general Stirling type having transverse upper drums connected by banks of tubes to a lower transverse drum or drums, a rear set of feed water tubes the upper ends of which are connected to one of the upper transverse drums, a plurality of superimposed boxes at the rear of the setting to which the lower ends of the economizer tubes are connected, a feed water inlet for the lower of said boxes, and connections between the boxes.

7. A boiler of the general Stirling type having upper and lower drums connected by banks of tubes, an economizer having tubes adjacent the rear of said banks and within the boiler setting, said economizer tubes having their upper ends connected to one of the

upper drums and their lower ends bent rearwardly, baffling arranged to give the gases serial up and down passes over the banks of tubes and the economizer tubes, the rear 5 vertical wall of the setting being located relatively closely adjacent the rearmost baffle to constitute a pass adapted to direct the gases along the vertical portions of said economizer tubes and across their bent ends, 10 and a header located in said vertical wall

and connected to the lower ends of said economizer tubes.

In testimony whereof I have hereunto signed my name in the presence of two subscribing witnesses.
